COMBINED LAMP CONTAINER AND
REFLECTOR

Herbert E. Plishker, Flushing, N. Y., assignor to
Westinghouse Lamp Company, a corporation
of Pennsylvania

Application October 21, 1931. Serial No. 570,108

2 Claims. (Cl. 240—103)

This invention relates to a combined container and reflector for photo flash lamps.

The photo flash lamp is a recent development and is used to facilitate the taking of flash light photographs and comprises a bulb similar to an electric incandescent lamp bulb containing a combustible material which when ignited gives an instantaneous, intense white light. The bulb is usually provided with a screw base which fits 5 the standard socket so that when the bulb is screwed into a socket and the circuit closed, current passes through the base to leads which cause an ignition element or resistance adapted to become heated to a temperature sufficiently 10 to ignite the combustible material. This material usually consists of crumpled, extremely thin sheets of aluminum foil, other light giving substances may be used but the aluminum foil has 15 been found the most practical.

As stated a photo flash lamp is provided with 20 a standard base which makes the device practical if it is to be used within reach of a standard socket. When using the lamp for the taking of pictures where no commercial current supply line is available it is the practice to use 25 a hand battery casing or holder having a socket to fit the base of the lamp so that the battery holder with the lamp thereon may be held in the hand and the lamp operated or flashed by 30 means of the usual thumb switch or button as provided on the usual flash light battery outfit.

When using a photo flash lamp it is obviously 35 desirable to direct as much of the emitted light as possible toward the object to be photographed and it is desirable to use a reflecting surface for this purpose but it is not always convenient to provide a reflector or to hold it in position.

It is an object of the present invention therefore 40 to provide a photo flash lamp with a practical and easily applied reflecting surface.

Another object of the invention is to provide 45 a reflecting surface which may be expeditiously and conveniently supported in proper relation to a photo flash lamp screwed into a socket.

Another object of the invention is to provide 50 a photo flash lamp container, the cover of which is convertible into a reflector.

Another object of the invention is to provide 55 a container for a plurality of photo flash lamps and a hand battery casing, the cover of said container being arranged for attachment to the casing in position to serve as a reflector for a photo flash lamp, and

Another object of the invention is to provide a container for a plurality of photo flash lamps adapted to serve as a combined shipping carton and reflector.

Other objects and advantages of the invention 60 will be more clearly understood by reference to the following description together with the accompanying drawings, in which

Fig. 1 is a perspective view of a container 65 constructed in accordance with the present invention;

Fig. 2 is a perspective enlarged view of the container shown in Fig. 1 but with the cover removed;

Fig. 3 shows the cover of the container at- 70 tached to a flash lamp casing and serving as a reflector for a photo flash lamp;

Figs. 4, 5, 6 and 7 show several modifications 75 of covers for photo flash lamp containers to serve as reflectors varying in their reflection surfaces;

Fig. 8 is a perspective view of a cylindrical form of container with the cover removed;

Fig. 9 shows the cover of the cylindrical container in position to serve as a reflector; 80

Fig. 10 shows a modification of the cover for the container shown in Fig. 8;

Fig. 11 is a perspective view of another modification of the container in which the entire 85 container may serve as a reflector;

Fig. 12 is a sectional view of the container taken on line XII—XII in Fig. 11;

Fig. 13 is a perspective view of the container 90 as used for a reflector, and

Fig. 14 is a sectional view of the container shown in Fig. 11 but with the sides spread to give a greater reflecting surface when in use as shown in Fig. 13.

Although the present invention is shown and 95 described herein as including a flash lamp battery casing it is to be understood that the invention broadly contemplates the utilization of the container or part thereof as a reflector and if desirable the same may be used when a photo flash lamp is operated on ordinary lighting 100 circuits.

A practical embodiment of the invention is shown in the accompanying drawings and may 105 comprise a shipping or storage carton 10 having a receptacle box 11 and a cover 12. The cover may be of any convenient or practical design having side flanges and may be provided with an extended flap or flange 13 having an aperture 14. The box 11 may be of any convenient size and may contain, as shown in 110

Fig. 2, three wrappers 15' containing photo flash lamps 15. The container is so proportioned that a space or pocket 16 is provided to receive a flash lamp casing 17. This casing 5 may be of any suitable form and may be provided with a socket 18 to receive the standard base 19 of the photo flash lamp.

A carton of three or more lamps may be sold together with the battery and when a lamp is to be used the socket portion of the battery casing 10 may be inserted into the aperture 14 which is of such dimension that it will snugly fit or may be screwed over the external threads of the socket 18 thus the cover will be held as shown in Fig. 3. It is to be understood that any suitable means may be employed to secure the cover 12 to the socket, the means shown being preferred on account of simplicity and cheapness. The aperture 14 may, if desirable, 15 be of such dimension as to fit the bulb neck and have a friction fit. It has been found preferable, however, to make the aperture of such diametrical dimension as to screw onto the outer threads of the socket on the battery casing.

20 When the reflector is attached to the socket a photo flash lamp 15 may be screwed in place and the assemblage may be held by the grip 20 of the battery casing 7 and the lamp flashed by a manipulation of the switch 21.

25 The cover or reflector 12 may be made in a variety of forms as shown in Figs. 4 to 7. Fig. 4 shows a cover 22 with semi-cylindrical surface 23. Fig. 5 shows a cover 24 in which the back reflecting surface 25 comprises two flat surfaces. 30 Fig. 6 shows a cover 26 with a plurality of flat surfaces 27. Fig. 7 shows a cover 28 having a deep and large area reflecting surface 29.

Fig. 8 shows a modified form of container 30 in which a plurality of wrappers 15' containing 40 photo flash lamps 15 are disposed, and in which space is provided to receive a flash light battery casing 17. The cover 31 is provided with an aperture 32 which is attached to a battery casing as shown in Fig. 9 when the photo flash 45 lamp is to be used.

Fig. 10 is a modification of the cover shown in Fig. 8 and is shaped with a curved reflecting surface 25'.

50 In Figs. 11 to 14 a container 33 is shown in which the entire box may serve as a reflector. An end 34 of the box has an aperture 35 to receive the socket 18 of the flash lamp battery

casing 17. The container 33 is provided with a cover comprising two swinging doors 36 and 37 and sides 38 and 39 of the box are expandable by reason of slotted flaps 40 and pins 41. Thus when the box is used as a reflector as shown in Fig. 13 the side walls 38 and 39 may be extended thus increasing the effective reflective area in conjunction with the doors 36 and 37. This construction gives a relatively large reflecting area and increases the efficiency of the lamp. 80 85

The present invention provides a compact photo flash light unit making it not only convenient for transportation but serves to keep the necessary equipment together and at the same time provides a handy effective reflector 90 at no appreciable added cost.

It will be noted that the selected container holds three lamps and the battery casing; the container may be of any desired size but by having the box to hold these lamps as shown, the 95 cover is proportioned of the proper relative size to serve as a reflector.

Obviously the box or the surface to be used as a reflector may, if desirable, be covered with a more highly reflective material than the white 100 paper or the metallic insert might be employed. It is to be understood, however, that such modifications as utilize the container structure as a reflector or modifications thereof, are within the spirit and scope of the present invention as 105 set forth in the appended claims.

What is claimed is:

1. A combined container and reflector comprising a receptacle to hold a plurality of photo flash lamps and a battery casing for operating 110 said lamps, a cover for said receptacle, said cover having a projection provided with an aperture for the insertion of said battery casing to support said cover in position to serve as a reflector for a lamp connected with said battery 115 casing for operation.

2. A combined container and reflector comprising a receptacle to hold a plurality of photo flash lamps and a casing for a battery to operate 120 said lamps, a cover having side flanges for said receptacle, one of said flanges having an aperture to receive an end of said battery casing to support said cover in position to serve as a reflector for a lamp connected with said battery 125 casing for operation. 125
